UNITED STATES PATENT OFFICE.

OTTAR S. LEE, OF CHICAGO, ILLINOIS, ASSIGNOR TO NYE TOOL AND MACHINE WORKS,
OF CHICAGO, ILLINOIS, A CORPORATION OF ILLINOIS.

DIE-MILLING MACHINE.

Application filed June 27, 1921. Serial No. 480,614.

To all whom it may concern:

Be it known that I, OTTAR S. LEE, a citizen of the United States, residing at Chicago, in the county of Cook and State of Illinois, have invented a new and useful Improvement in Die-Milling Machines, of which the following is a specification.

My invention relates, more particularly, to the cutting of threads on dies, and especially to machines wherein provision is made for producing the desired threads in "backed off," or relieved, condition; and my primary objects, generally stated, are to provide a novel, simple and positively-operating construction of means for effecting the "backing-off" of the threads, and to cause the dies produced to be uniform and present the internal contour at the threads thereof, best adapted to the accurate formation of threads cut by the die; and other objects as will be manifest from the following description.

I have devised my invention for embodiment, more particularly, though not to the exclusion of its embodiment in other constructions of machines, in machines of the general construction illustrated and described in my pending application for United States Patent, Serial No. 397,458, filed July 19, 1920, and have therefore chosen to illustrate it in such a construction of machine.

Referring to the accompanying drawings:

Figure 1 is a view in side elevation of a machine in which my improvements, constructed in accordance with one of the embodiments of my invention, are incorporated. Figure 2 is an enlarged plan view of the die-blank-holding mechanism and the means whereby the desired relative movement of the die-blank and the milling device, is effected. Figure 3 is a view in end elevation of the mechanism shown in Fig. 2, the latter being viewed in the direction of the arrow in Fig. 2. Figure 4 is a view in elevation of the opposite end of the mechanism of Fig. 2. Figure 5 is a view in side elevation of the mechanism of Fig. 2, with a certain part of the housing broken away to disclose an interior detail, with the lowermost member shown in perspective. Figure 6 is a section taken at the line 6—6 on Fig. 2 and viewed

in the direction of the arrows, the lowermost member also being shown in perspective. Figure 7 is a plan view with one of the parts shown in section and parts broken away, of the mechanism at the right hand side of Fig. 5. Figure 8 is a section taken at the irregular line 8—8 on Fig. 6 and viewed in the direction of the arrows. Figure 9 is a plan sectional view taken through the mechanism for returning the work-holder to normal position. Figure 10 is a broken section taken at the irregular line 10—10 on Fig. 6 and viewed in the direction of the arrows. Figure 11 is a section taken at the irregular line 11—11 on Fig. 3 and viewed in the direction of the arrows. Figure 12 is a face view, with certain parts broken away, and in the nature of a diagram, of the mechanism for shifting the structure supporting the die-blank, to effect the "backing off" of the threads, the parts shown being viewed in the direction of the arrow in Fig. 2 and being shown in one of the positions it assumes during the cutting of the threads. Figure 13 is a similar view showing the mechanism in the position it assumes following the thread-cutting movement. Figure 14 is a view like Fig. 2 of another of the many forms in which my invention may be provided. Figure 15 is a view like Fig. 3 of the structure shown in Fig. 14. Figure 16 is a view like Fig. 12 of the mechanism of Figs. 14 and 15 whereby the "backing off" of the threads is effected, this mechanism being shown in the position it assumes during the cutting of the thread; and Figure 17, a view like Fig. 16 showing a position assumed by the "backing off" mechanism following the cutting of the thread.

The particular construction of machine illustrated is designed for use in the producing of threads on die-blanks of a type commonly known, and formed of an irregularly-shaped body of steel with an opening therethrough into which lug-portions, which form the thread segments, when threaded, extend, such a blank being shown in Fig. 10 wherein it is represented at 25, the opening therein being shown at 26 and the lug-portions referred to at 27, there being four of these lug-portions in the particular construction of blank shown, the inner surface of each of

2
which is to be threaded to form the cutting portions of the die, these lug-portions being equidistantly spaced about the opening 26 in the blank, though it will be understood from 5 the following that the invention is not limited to use in the manufacture of the particular form of die shown.

The milling device and work-holding device are mounted on a bed, the work-holding device 10 preferably to be movable lengthwise of the milling device, such a bed, and which is common in lathe constructions, being indicated at 28 upon which a carriage, forming a part of the work-holding device and 15 represented at 29 and extending transversely of the bed, is mounted to slide lengthwise of the bed, the latter, in practice, being provided with means, such as, for example, those commonly used in lathes for shifting 20 the tool-holder thereof, for moving the carriage 29 lengthwise of the bed and the milling device 31 the spindle of which, represented at 300, is secured at one end in the head-stock 30', to be rapidly rotated thereby, 25 and journaled at its opposite end in a tail-stock (not shown) on the bed 28, the milling device extending through the work-holding device and its operating mechanism supported on the carriage 29 and hereinafter 30 described.

Mounted on the carriage 29 to extend transversely of the bed 28 is a base 32, there being provided between this member and the carriage 29 guiding means for causing the 35 base member 32 to move in a predetermined path crosswise of the bed when adjusted thereon, for the purpose hereinafter explained. The guide-means shown comprise a dovetailed rib 33 provided on the upper 40 surface of the carriage 29 and extending into a dovetailed channel 34 in the bottom of the base 32 longitudinally of the latter, the rib 33 being disposed at a right angle to the axis about which the milling device 31 carried by the spindle 300 rotates, for a purpose 45 hereinafter explained. The channel 34 also contains a gib 35 cooperating with set-screws (not shown) for rigidly holding the base 32 on the carriage 29 in position of adjustment thereon, effected by means of any 50 suitable device, as for example that commonly used on the tool-holders of lathes for adjusting the tools toward and away from the work and including a depending lug 37 55 on the member 34 in which a screw shaft (not shown) provided on the carriage 28, and equipped with a hand wheel 38, screws. The upper surface of the base 32 is provided with a dovetailed rib 39 extending 60 lengthwise thereof and crosswise of the bed at an angle slightly oblique to the axis about which the milling device 31 rotates, the rib 39 being located within a dovetailed channel 40 provided in the bottom surface of a

sub-base member 41 which also extends 65 crosswise of the bed and is adapted to slide, guided by the rib 39, on the base 32. The sub-base 41 is provided adjacent its opposite ends with upwardly-extending bosses 42 through which a shaft 43 extends, this shaft 70 also extending through pairs of lugs 44 depending from the base 45 of a housing member 46, and through the medium of which shaft the housing member 46 and the parts carried thereby are pivotally connected with 75 the sub-base 41 adapting the said housing, with its several parts, to be tipped in a vertical plane. The edge portion of the base 45 opposite that equipped with the lugs 44, is provided with adjustable stop devices shown 80 as screws 47 threaded in the base-portion 45 and bearing at their lower ends against the upper surface of the sub-base 41, the adjustment thus provided permitting of the setting of the base portion 45 at any desired angle 85 relative to the horizontal plane, the base-portion 45 being also provided with screws 48 which extend outwardly therethrough and screw at their lower ends into threaded openings 49 in the sub-base 41 thereby cooperating 90 with the adjusting screws 47 to firmly secure the base-portion 45 in adjusted position. While the member 46 is shown as extending vertically, in use this last-referred-to member would be tipped to 95 the right in Fig. 6, on the hinge 43, and set in such position by the screws 47 and 48 to extend at an oblique angle to the axis of the milling device, for the purpose hereinafter described.

The housing portion 46 is formed with an inwardly-extending annular flange 50 which is threaded at its inner periphery, as indicated at 51 (Fig. 6), to present a thread 105 having the same pitch as that of the segmental threads to be formed on the die-blank, the thread 51 forming a lead-screw for cooperation with that part of the structure on which the die-blank is held, the parts described being preferably so positioned and positioned, as shown, as to cause the axis of the milling cutter 31 to extend midway between the upper and lower portions of the bore in the housing member 46. Located within the housing 46 110 is a rotatable hollow member 52 of circular shape in cross-section threaded between its ends, as indicated at 53, at which thread it screws into the thread 51. At one side of 115 its threaded portion 53 the member 52 is equipped with a gear 54 which extends into a recess 55 in the housing 46, this end of the member 52 extending at a reduced portion 56 thereof, outwardly through the housing 46, the latter containing in a face 120 thereof an annular recess 57 in which a removable ring 58, secured in place by screws 59, is located, this ring 125 extending

into overlapping position relative to the gear 54. The outer end of the member 52 is annularly recessed, as indicated at 69, and contains a plate 61 secured to the member 52, as by means of the screws 62, the plate 61 constituting a part of the mechanism for holding in place the die-blank to be cut. The opposite end of the member 52, and represented at 63, is surrounded by a tubular member 64 in which the member 52 may be rotated except when clutched thereto as hereinafter described. The tube member 64 extends through the opening 65 in a ring 66 mounted in an annular recess 67 in the end of the housing 46 opposite that containing the recess 57 and secured therein as by the screws 68, the outwardly-extending end of the member 64 having secured thereon, as at the threaded connection 69, a ring 70 containing an annular recess 71 in its inner face. The member 64 constitutes one element of a clutch device through the medium of which the member 52 is rotated in the housing 46, the member 64 to this end containing in a face thereof, that which is disposed at the right hand side of Fig. 5, pairs of notches 72, preferably diametrically opposed, these notches cooperating with pairs of lugs 73 also diametrically opposed and carried by the member 52, these lugs being preferably formed on plates 74 which are set into the threaded periphery 53 of the member 52 to be inset relative to the threads thereon and held in place, as by the screws 75. The member 64 is slideable lengthwise on the member 52 for moving the cooperating clutch elements referred to into and out of interlocking position to connect together, or disconnect, the members 52 and 64 for driving the former from the latter at will. The member 64 is provided with a flange 76 equipped with plungers 77 which guidingly extend into sockets 78 provided in a face of a worm wheel 79 surrounding the member 64 and splined thereon, to cause the member 64 and the worm wheel 79 to rotate together, the latter abutting the inner face of the ring 66. The plungers 77 have reduced portions 80, and are provided with shoulders 77^a these plungers extending parallel with the axis of the worm wheel 79 and guidingly extending into openings 81 in the wheel 79, the sockets 78 containing coil springs 82 which surround the plungers 77 and by bearing at their opposite ends against the bases of the sockets 78 and the shoulders 77^a, yieldingly force the member 64 to the right in Fig. 6 to a position in which the clutch device hereinbefore referred to clutches the members 52 and 64 together when the notches 72 and lugs 73 are in alinement.

Means are provided for controlling the throwing of said clutch into and out of

clutching position, these means, as shown, 63 being formed of a lever 83 fulcrumed between its ends on a pin 84 supported in brackets 85 extending from the housing 46, the lower end of this lever being forked to provide the curved arms 86 which are 70 equipped with inwardly-extending rollers 87 journaled thereon through the medium of the headed pins 88, these rollers extending into the annularly recessed portions 71 of the ring 70 and bearing against the inner 75 side of the latter as represented (Fig. 5), it being understood that in the swinging of the lever 83 in clockwise direction in Figs. 5 and 6, the member 64 is shifted to the left in these figures to separate the members of 80 the clutch device described.

The worm wheel 79 is driven through the medium of a worm 89 secured to a shaft 90 journaled in the housing 46 and shown as provided with a hand wheel 91 for rotating 85 it. In this connection it may be stated that the machine as shown is adapted to be operated through the medium of the shaft 90, rotated by hand, but will be readily understood that, if desired, it may be driven from 90 a power device and, where desirable, any suitable means for automatically arresting rotation of the shaft 90 thus driven, and after a die has been threaded, may be provided.

Through the medium of the drive mechanism just referred to the member 52 which, as hereinbefore explained, supports the die-blank 25 to be operated on, is caused to be rotated in clockwise direction in Fig. 3 to 100 cause it to make a practically complete revolution, the member 52 gradually moving inwardly, viz., to the left in Fig. 6, into the housing 46 by reason of its threaded connection therewith, the lengthwise travel of 105 the member 52 being equal to the distance between any two adjacent portions of the thread 51. The work-holder shown comprises the plate 61 provided on its outer face with a plurality of bosses 92 preferably disposed in rectangular arrangement around the opening 93 in this plate and against which the blank 25 is adapted to bear at a face thereof. At one side of the opening 93 the plate 61 is provided with a laterally-extending lug 94 in the form of a bar 110 equipped with bosses 95 spaced apart and against which the die-blank bears at an edge thereof. The plate 61 is also provided with a laterally-extending portion 96 preferably 115 disposed at a right angle to the bar 94 and provided with a laterally-extending boss 97 against which the die-blank bears at another edge thereof. The extension 96 is slotted as indicated at 98 to provide the three 120 lugs 99, 100 and 101 through which a pivot pin 102 extends, the inner face of the plate 103 being provided with bosses 105 prefer-

ably disposed in a rectangular arrangement thereon and in line with the lugs 92, respectively. The opposite end of the plate 103 contains a slot 106, the outer face of the plate 5 at the portions thereof flanking this slot tapering in the direction as indicated at 107 (Fig. 7). This portion of the plate 103 cooperates with a clamping device shown as formed of a rod 108 pivoted at its inner end 10 on a pivot pin 109 confined in ears 110 extending laterally from the plate 61. The rod 108 is formed with a head 111 at which the pivoting referred to is effected, the edge portion of this head which opposes the die-blank 25, when the latter is introduced into the holder, being preferably in the form of a cam as represented at 112. The rod 108 extends through the slot 106 and is provided at its outer, threaded, end with a nut 113 preferably having a curved inner end portion as represented at 114 which bears against the tapered surfaces 107 of the plate 103. The plate 61 is also provided on its outer face, and diametrically opposed to the bar portion 94, with a pair of laterally-extending ears 115 containing a pivot pin 116 which extends through, and forms a pivot for, a rocking member 117, the free edge of which is preferably curved as represented at 118, the member 117 being outwardly pressed by a spring 117^a. The member 117 cooperates with an operating device therefor shown as formed of a rod 119 extending loosely through an opening 120 in the member 117 30 and engaging the outer face of this member at a shoulder 121 on the rod, this rod having threaded engagement at its inner end with an opening 122 in the plate 61. It may be here stated that in the positioning of the die-blank in the holder, the operator, assuming the actuating device formed of the rod 108 to be swung outwardly, introduces the die-blank 25 into a position wherein it rests upon the bosses 95 and against the boss 97. 40 The operator then swings the plate 103 toward the die-blank and the operating member formed of the rod 108, into a position wherein the rod portion extends into the slot 106 and the nut 113 opposes the tapered surface 107 of the plate 103. Upon tightening the nut 113 on the rod 108 the engagement of the nut with the tapered surface 107 operates to swing the rod 108 in counter-clockwise direction in Fig. 7 thereby causing the cam surface 112 to ride against the adjacent edge of the die-blank and force it rigidly up against the boss 97, the manipulation of the nut as stated also serving to firmly force the blank against the bosses 92. 50 The operator then swings the member 117 toward the plate 61 and into engagement at its surface 118 with the adjacent edge of the die-blank 25, to exert a clamping force against this edge of the plate, by screwing the

rod 119 into the plate 61, the construction of work-holder described operating to very firmly hold the die-blank in position on the member 52. In the machine illustrated, the die-blank is caused, during the cutting of each segment 27, to be bodily shifted to the left 65 in Fig. 3, thereby producing the "backing off", or relieving, of the die at each of its segments, the die-blank being shifted in the opposite direction to cause the die-blank and the milling device 31 to occupy the necessary 70 relative positions for cutting the next segment to "backed off" condition, before the next segment has moved into engagement with the milling device, a description of the means shown for this purpose being as follows: 75

Mounted on the base 32 at the left hand end thereof in Fig. 3, is a block 123 provided with a depending tongue 124 located within a groove 125 in the upper surface 85 of the base 32 whereby this block may be guidingly adjusted lengthwise of the base, the block 123 being provided with set-screws 126 for securing it in adjusted position. The block 123 is provided with upwardly-extending ears 127 spaced apart and into the space between which the lower end of a lever 128 extends, this lever being pivoted to the ears through the medium of a pivot bolt 129. The lever 128 is pivotally connected, through the medium of a pivot bolt 130, with the outer ends of a pair of links 131 spaced apart and arranged at opposite sides of this lever, the inner ends of these links being located at opposite sides of an 100 ear 132 provided on, and extending laterally from, a block 133 rigidly secured, as by means of the screws 134, to the housing 46, the links 131 being pivotally connected with an ear 132, as through the medium of a 105 pivoting bolt 136. The upper end of the lever 128 is provided with a stud 137 extending laterally therethrough in opposite directions on the protruding ends of which rollers 138 are journaled, these rollers extending into slots 139 provided in the bifurcated head portion 140 of a lever 141, pivoted at its opposite end, as indicated at 110 142, to an upwardly-extending ear 143 provided on the casing 46, the side arms of the 115 bifurcated head 140 being spaced apart and the lever 128 extending between these arms. The lever 141 is preferably formed of the bar 141^a, a bar 141^b and a block 141^c interposed between the bars 141^a and 141^b, these 120 parts being held together by a pin 144 and a bolt 145. The block 141^c extends short of the right hand end of the lever 141 in Fig. 3 whereby this lever presents at the extremities of its bars 141^a and 141^b spaced portions 125 between which the lug 143 extends and through which the pivoting bolt 142 passes. The location of the opposite side walls of

the slots 139 and which are engaged by the rollers 138, is such that as the lever 141 is rocked on its fulcrum 142 it will produce a rocking of the lever 128 on its fulcrum 129, the walls referred to of these slots being preferably of arc shape and struck from a center preferably a slight distance above the axis of, and in a direct vertical line with, the axis of the pivot 142 as shown in the drawings (Fig. 3), whereby in the upward movement of the lever 141 the lever 128 is shifted to the right in Fig. 3 and on the downward movement of the lever 141 the lever 128 is shifted to the left in this figure, the means shown for actuating the mechanism just described being as follows: Journaled in the housing 50 is a shaft 146 equipped with a hand wheel 147 and carrying a pinion 148 rigid thereon which is in mesh with the gear 54, the shaft 146 carrying a disk 149 in which a pin 150 arranged eccentric of the axis of the shaft 146, is secured. Pivoted at its lower end on the pin 150 is a link 151, its upper end being pivotally connected, by means of the pivot pin 152, with the lever 141 at a point between the ends of the latter, whereby in the rotation of the pinion 148, by the rotation of the gear 54, the link 151 will be caused to be bodily raised and lowered and the lever 141 to be rocked, the proportions of the pinion 148 and gear 54 being such that the shaft 146 will make four complete revolutions with each revolution of the gear 54, where the die-blank to be operated on is provided with four segments to be threaded as in the case of the blank shown, thereby to cause the sub-base 41 and the parts carried thereby to make four complete reciprocations with each complete rotation of the work-holder.

The gear 54 is provided at its opposite faces with projections 153 and 154 which may be afforded by providing the gear 54 with a pin extending therethrough and projecting at its ends beyond the opposite faces of the gear, the projection 154 being adapted to cooperate with a stop surface 155 on the face of the ring 58 opposing the gear 54, and the projection 153 being adapted to cooperate with a stop surface 156 provided on the housing 46 and extending into the recess 55. The stop surfaces 153 and 154 are provided for the purpose of limiting the rotation of the member 52, and consequently the work-holder, in both directions, the structure being designed to permit the member 52 to make practically one complete rotation only from initial, starting, position. In the starting position the projection 154 engages the stop surface 155 as shown in Fig. 10, and in the rotation of the gear 54 one revolution, during which operation the gear 50 and the parts connected therewith move to the left in Fig. 5 by reason of the rotation of the member 52 within the threads of the housing 50, the projection 153 engages the stop surface 156. The operation of the machine is as follows: Assuming that the parts of the machine are in normal position and the work-holder is empty, the operator introduces the die-blank to be operated on, represented at 25, into the holder to seat it upon the stop surfaces 95 and against the stop surface 97. The pivoted clamping plate 103 is then swung at its hinge connection with the member 52 toward and into contact with the outermost face of the die-blank, and the pivot rod 108 is then swung to a position in which it extends into the slot 106 in the plate 103. The nut 113 is then screwed upon the rod 108 and toward the plate 103 in which operation the nut is forced against the tapered surface 107 of said plate with the result of causing the rod 108 to swing to the right in Fig. 7 which not only forces the plate 103 into rigid clamping engagement with the die-blank 25 to thus firmly clamp it between this plate and the member 61, but also, by reason of the clamping action exerted by the cam member 111 on the rod 108 and engaging the adjacent edge of the die-blank, forces the latter rigidly against the stop surface 97 thereby clamping the plate firmly in a lateral direction. The operator then, by manipulating the screw 119, wedges the member 117 against the upper edge of the die-blank which firmly clamps the latter between the member 117 and the stop surface 95.

Assuming the milling device 31 to be rotating, the operator, to effect the thread-cutting operation, rotates the shaft 90 which, in turn, through the medium of the worm 89, rotates the worm wheel 79 and, through the medium of the clutch mechanism described, rotation of the member 52 carrying the work is effected, the work rotating in clockwise direction in Figs. 3, 8, 10, 12 and 13 and the milling device being shown as rotating upon its axis in the opposite direction as indicated by the arrows in Figs. 12 and 13. In the normal position of the machine, the segment to be first threaded, viz., the lowermost one at the left hand side of Fig. 10, is below the plane of the cutting members of the milling device and the crank-pin 150 is in such position that its axis extends to the right of, and below, the axis of the shaft 146, viewing the machine in Figs. 3, 12 and 13, in which position of the parts the housing 46 and the parts carried thereby are disposed at a point intermediate the extremities of their stroke. Rotation of the shaft 90 as stated rotates the shaft 146 in counter-clockwise direction in Figs. 12 and 13, thus causing the lever 141, through the link connection 151 to be rocked on its pivot 142 in clockwise direction (Fig. 130

3) with the result, by reason of the engagement of the rollers 138 with the slotted portion of the lever 141, of swinging the lever 128 in clockwise direction (Fig. 3) on its 5 fulcrum 129, thereby slowly shifting the housing 46 and the parts carried thereby to the right in Fig. 3. The shifting of the housing, as stated, continues until the segment referred to reaches substantially the 10 position shown in Fig. 12, the continued rotation of the shaft 90 operating through the link connection 151 to swing the lever 141 around its pivot 142 in counter-clockwise direction in Fig. 3 with the result of causing the lever 128 to swing in counter-clockwise direction on its pivot 129 and thereby slowly shift the housing 46, and the parts carried thereby, to the left in Fig. 3, the shifting of the housing as last stated continuing 15 throughout the time that the segment last referred to continues in engagement with the milling device (see Fig. 13), with the result of causing the thread cut on this segment to recede from the center opening of 20 the blank, thereby producing what is known as a relieved, or "backed off", condition of the thread.

The various links and levers described and forming the mechanism by which the housing 46, and the parts carried thereby, is reciprocated as stated, are so proportioned and connected together with the housing 46 and base 123, as shown in the drawings, that this mechanism will operate smoothly to perform 25 its function and by the exertion of comparatively slight turning force applied to the shaft 90. At the conclusion of the cutting of the thread on the segment last referred to, and before the next segment 27, by the continued rotation of the shaft 90, is moved 30 into engagement with the milling device, the crank-pin 150 will have again moved to the position occupied thereby in the normal position of the machine hereinbefore referred to, and the work-holder will thus have become repositioned, by moving to the right in Fig. 3, for causing the segment last referred to to be operated on by the milling device in the continued operation of 35 the machine as explained of the segment first referred to, the crank-pin 150 making four complete revolutions for each revolution of the work-holder.

Upon the conclusion of the cutting of 40 this last-referred-to segment, the housing 46 again shifts to the right in Fig. 3 while the next, third, segment is being carried into a position to be operated on by the milling device, this third segment being cut as explained of the first segment, and during the shifting of the housing 46 to the right for the fourth time, and partial rotation of the member 52, the fourth segment is cut. At 45 the conclusion of the cutting of these four segments the member 50 will have completed

practically a complete revolution and in doing so further rotation thereof is arrested by the engagement of the stop 153 with the stop 156. Inasmuch as the member 52 engages at its thread 53 with the threaded portion 51 of the housing 46, which thread is of the same pitch as the thread to be cut on the die, the member 52 will move lengthwise in a single rotation, a distance equal to the pitch of the thread 51, and in adjusting the 70 boss 45 on the sub-base 41 at the hinging shaft 43, before the cutting operation begins, to cause the die-blank to extend at an angle to the axis of the milling device corresponding with the angle of the lead of the 75 thread desired to be formed on the segments of the blank, extends, such threads are caused to be accurately formed.

From the foregoing it will be understood 80 that the four segments of the die-blank are cut, to thread the same, in succession, and that each is in "backed off," or relieved, condition.

The mechanism is so constructed and arranged that the milling device operates to 85 cut the segments in a direction toward what becomes, in the finished die, the cutting edges thereof or, in other words, from the back toward the front, or cutting edge, of the segment, as will be clear from the drawings (see Fig. 13), this being of advantage 90 as the cutter elements of the milling device during the cutting of those portions of the segments at which the cutting edges of the threads extend in the finished die, cut 95 against a lesser body of metal than they would if the reverse operation occurred, thereby causing the finished threads to present clean cutting edges.

In the particular construction illustrated 100 provision is made for causing the threaded opening in the die to taper from its front face, viz., the face of the die which would extend at the right hand side of Fig. 6 and at 105 which the die in use is applied to the article 110 on which the thread is to be cut, toward its rear face, viz., the portion of the die which is the last to operate on the article to be threaded by the die, and this is accomplished 115 in the particular illustrated embodiment shown by disposing the guide rib 39 obliquely relative to the axis about which the milling device rotates.

Inasmuch as the work inclines relative to 120 the milling device to produce the tapered threaded opening in the die, it is desirable to provide the cutter elements on the milling device in such form that instead of the converging cutting edges of the cutter elements 125 extending at equal angles to the axis of the cutter they shall extend at slightly different angles thereto to offset for the obliqueness of the angle between the face of the work and the axis of the milling device and cut a thread the converging edges of which shall 130

extend at the same angle to the axis of the finished die after a die-blank has been threaded, as described.

The operator, to return the member 52 to normal position in the housing 46, throws the lever 83 into a position in which the cooperating clutch elements 72 and 73 are out of mesh thereby permitting the member 52 to be turned at its threaded connection 10 with the housing 46 throughout practically a complete revolution to normal condition, in which the member 52 moves to the right in Fig. 6, by rotating the hand wheel 147.

It will be understood from the drawings 15 and from the foregoing description that the machine is adapted, by reason of the adjustments provided therein, for use in the forming of dies the internal diameters of which vary.

20 It will also be understood that in the cutting of threads on dies of different internal diameters, the angle at which the work is caused to extend relative to the axis of the milling device, determined by its adjustment 25 on the hinge-pin 43, should be varied to cause this angle to correspond with the angle of the lead of the thread to be produced.

Referring now to the embodiment of my invention shown in Figs. 14 to 17 inclusive, 30 and relating to the mechanism for shifting the sub-base 41 and the parts carried thereby to effect the "backed off" condition of the threads of the segments, the mechanism of these figures is the same as that of the preceding figures except that, instead of providing a single lever like the lever 141 with the pin and slot connection between it and the lever 128, I provide a toggle lever represented at 200 and formed of the two link-sections 201 and 202 pivotally connected by a pin at 203, the outer end of the link-section 201 being pivotally connected with the upper end of the lever 128, by means of the pivot pin 204, and the outer end of the link-section 202 being pivotally connected at the pin 205, to an upstanding ear 206 rigid with the housing 46. The link 201 is preferably formed of two flatwise opposed sections 201^a which straddle the lever 28 and the link 202 is preferably formed of two link-sections 202^a and an intermediate block 250 secured to the sections 202^a by pins 251, one end of one of the link sections 202^a extending 45 between the adjacent ends of the link sections 201^a through which and the other of the link-sections 202^a the pivot pin 203 extends.

The various links and levers described 50 and forming the mechanism by which the housing 46, and the parts carried thereby, is reciprocated as stated, are so proportioned and connected together with the housing 46 and base 123 as shown in the drawings, that this mechanism will operate smoothly 55 to perform its function and by the exertion

of comparatively slight turning force applied to the shaft 9.

While I have illustrated and described certain constructions embodying my invention, I do not wish to be understood as intending to limit it thereto as the same may be variously modified and altered without departing from the spirit of my invention, and the invention may be embodied in other forms of structures than those shown.

What I claim as new, and desire to secure by Letters Patent, is:

1. In a machine of the character set forth, the combination of a base member, a second member movable on said base member, 80 and means for moving said second member on said base member comprising mechanism formed of relatively movable elements operatively engaged together, said mechanism operatively engaging said base member and 85 said second member at opposite sides of the point at which said elements operatively engage each other, and means for effecting relative movement of said elements.

2. In a machine of the character set forth, 90 the combination of a base member, a second member movable on said base member, and means for moving said second member on said base member comprising mechanism formed of relatively movable elements op- 95 eratively engaged together, said mechanism operatively engaging said base member and said second member, and means operatively engaging said mechanism between its points of connection with said base member and 100 said second member, for effecting relative movement of said elements.

3. In a machine of the character set forth, the combination of a base member, a second member movable on said base member, 105 and means for moving said second member on said base member comprising mechanism formed of relatively movable elements op- 110 eratively engaged together, said mechanism operatively engaging said base member and operatively engaging, by a plurality of said elements, with said second member at a plu- 115 rality of points, and means for effecting relative movement of said elements.

4. In a machine of the character set forth, 115 the combination of a base member, a second member movable on said base member, and means for moving said second member on said base member comprising mechanism formed of relatively movable elements op- 120 eratively engaged together, said mechanism operatively engaging said base member and operatively engaging, by a plurality of said elements, with said second member at a plu- 125 rality of points, and means operatively engaging said mechanism between its point of connection with said base member and one of its points of connection with said second member, for effecting relative movement of said elements.

5. In a machine of the character set forth, the combination of a base member, a second member movable on said base member, and means for moving said second member on said base member comprising mechanism formed of relatively movable elements operatively connected together, one of said elements being a lever fulcrumed on said base member with a connection to said second member, and another of said elements operatively engaging said second member at a point non-coincident with the point of engagement of said connection with said second member, and means for effecting relative movement of said elements.
6. In a machine of the character set forth, the combination of a base member, a second member movable on said base member, and means for moving said second member on said base member comprising mechanism formed of relatively movable elements operatively connected together, one of said elements being a lever fulcrumed on said base member with a connection to said second member between the ends of said lever, and another of said elements operatively engaging said second member at a point non-coincident with the point of engagement of said connection with said second member, and means for effecting relative movement of said element.
7. In a machine of the character set forth, the combination of a base member, a second member movable on said base member, and means for moving said second member on said base member comprising mechanism formed of relatively movable elements operatively connected together, one of said elements being a lever fulcrumed on said base member with a connection to said second member, and another of said elements operatively engaging said second member at a point non-coincident with the point of engagement of said connection with said second member, and means operatively engaging said mechanism between the points of engagement of said mechanism with said second member, for effecting relative movement of said elements.
8. In a machine of the character set forth, the combination of a base member, a second member movable on said base member, and means for moving said second member on said base member comprising mechanism formed of relatively movable elements operatively connected together, one of said elements being a lever fulcrumed on said base member with a connection to said second member between the ends of said lever, and another of said elements operatively engaging said second member at a point non-coincident with the point of engagement of said connection with said second member, and means operatively engaging said mechanism between the points of engagement of
9. In a machine of the character set forth, the combination of a base member, a second member movable on said base member, and means for moving said second member on said base member comprising mechanism formed of relatively movable elements operatively connected together including levers pivoted to said base member and said second member, respectively, and operatively connected together, with a connection between said second member and the one of said levers pivoted to said base member, and means for effecting relative movement of said elements.
10. In a machine of the character set forth, the combination of a base member, a second member movable on said base member, and means for moving said second member on said base member comprising mechanism formed of relatively movable elements operatively connected together including levers pivoted to said base member and said second member, respectively, and operatively connected together, with a connection between said second member and the one of said levers pivoted to said base member, the operative connection between said elements being between the connections of said levers with said base member and said second member.
11. In a machine of the character set forth, the combination of a base member, a second member movable on said base member, and means for moving said second member on said base member comprising mechanism formed of relatively movable elements operatively connected together, including levers pivoted to said base member and said second member, respectively, one of said levers presenting a cam surface engaged by the other of said levers, and means for actuating one of said levers.
12. In a machine of the character set forth, the combination of a base member, a second member movable on said base member, and means for moving said second member on said base member comprising mechanism formed of relatively movable elements operatively connected together, including levers pivoted to said base member and said second member, respectively, one of said levers presenting a cam surface engaged by the other of said levers, and means for actuating the one of said levers presenting said cam surface.
13. In a machine of the character set forth, the combination of a base member, a second member movable on said base member, and means for moving said second member on said base member comprising mechanism formed of relatively movable elements operatively connected together, in-

cluding levers pivoted to said base member and said second member, respectively, the one of said levers pivoted to said second member presenting a cam surface engaged by the other of said levers, and means for actuating one of said levers.

14. In a machine of the character set forth, the combination of a base member, a second member movable on said base member, and means for moving said second member on said base member comprising mechanism formed of relatively movable elements operatively connected together, including levers pivoted to said base member and said second member, respectively, the one of said levers pivoted to said second member presenting a cam surface engaged by the other of said levers, and means for actuating said last-referred-to lever.

15. In a machine of the character set forth, the combination of a base member, a second member movable on said base member, and means for moving said second member on said base member comprising mechanism formed of relatively movable elements operatively connected together, including levers pivoted to said base member and said second member, respectively, with the connection between said second member and the one of said levers pivoted to said base member, one of said levers presenting a cam surface engaged by the other of said levers, and means for actuating one of said levers.

16. In a machine of the character set forth, the combination of a base member, a second member movable on said base member, and means for moving said second member on said base member comprising mechanism formed of relatively movable elements operatively connected together, including levers pivoted to said base member and said second member, respectively, with the connection between said second member and the one of said levers pivoted to said base member, one of said levers presenting a cam surface engaged by the other of said levers, and means for actuating one of said levers presenting said cam surface.

17. In a machine of the character set forth, the combination of a base member, a second member movable on said base member, and means for moving said second member on said base member comprising mechanism formed of relatively movable elements operatively connected together, including levers pivoted to said base member and said second member, respectively, with a connection between said second member and the one of said levers pivoted to said base member, the other of said levers presenting a cam surface engaged by the one of said levers connected with said base member, and means for actuating one of said levers.

18. In a machine of the character set forth, the combination of a base member,

a second member movable on said base member, and means for moving said second member on said base member comprising mechanism formed of relatively movable elements operatively connected together, including levers pivoted to said base member and said second member, respectively, with a connection between said second member and the one of said levers pivoted to said base member, the other of said levers presenting a cam surface engaged by the one of said levers connected with said base member, and means for actuating said cam-equipped lever.

19. In a machine of the character set forth, the combination of a base member, a second member movable on said base member, and means for moving said second member on said base member comprising mechanism formed of relatively movable elements operatively connected together, including levers pivoted to said base member and said second member, respectively, one of said levers presenting a cam surface of general curved form eccentric of the axis about which said lever moves, said cam surface being engaged by the other of said levers, and means for actuating said cam-equipped lever.

20. In a machine of the character set forth, the combination of a base member, a second member movable on said base member, and means for moving said second member on said base member comprising mechanism formed of relatively movable elements operatively connected together, including levers pivoted to said base member and said second member, respectively; the one of said levers which is pivoted to said second member presenting a cam surface of general curved form, extending eccentrically of the axis about which said lever operates, said cam surface being engaged by the other of said levers, and means for actuating said cam-equipped lever.

21. In a machine of the character set forth, the combination of a base member, a second member movable on said base member, and means for moving said second member on said base member comprising mechanism formed of relatively movable elements operatively connected together, including levers pivoted to said base member and said second member, respectively, with a connection between said second member and the one of said levers pivoted to said base member, the one of said levers pivoted to said second member containing a cam surface of general curved form, extending eccentrically of the axis about which said lever operates, said cam surface being engaged by the other of said levers, and means for actuating said cam-equipped lever.

22. In a machine for cutting threads on an object, the combination of a holder-mem-

- ber for the object to be threaded, a cutting member for threading the object, one of said members being movable toward and away from the other thereof during the thread-cutting operation to produce backing-off of the threads, a support for said movable member, and means for effecting said movement of said last-referred-to member comprising mechanism formed of relatively movable elements operatively engaged together, said mechanism operatively engaging said support and said movable member at opposite sides of the point at which said elements operatively engage each other and means for effecting relative movement of said elements.

23. In a machine for cutting threads on an object, the combination of a holder-member for the object to be threaded, a cutting member for threading the object, one of said members being movable toward and away from the other thereof during the thread-cutting operation to produce backing-off of the threads, a support for said movable member, and means for effecting said movement of said last-referred-to member comprising mechanism formed of relatively movable elements operatively engaged together, said mechanism operatively engaging said support and said movable member and means operatively engaging said mechanism between its points of connection with said support and said movable member for effecting relative movement of said elements.

24. In a machine for cutting threads on an object, the combination of a holder-member for the object to be threaded, a cutting member for threading the object, said holder-member being movable toward and away from the cutting member during the thread-cutting operation to produce backing-off of the threads, a support for said holder-member, and means for effecting said movement of said holder member comprising mechanism formed of relatively movable elements operatively engaged together, said mechanism operatively engaging said support and said holder member and means for effecting relative movement of said elements.

25. In a machine of the character set forth, the combination of a base member, a second member movable on said base member, and means for moving said second member on said base member comprising mechanism formed of relatively movable elements operatively engaged together, said mechanism operatively engaging said base member and said second member and including pivotally supported relatively movable levers engaging each other, and means for actuating said mechanism.

27. In a machine of the character set forth, the combination of a base member, a second member movable on said base member, and means for moving said second member on said base member comprising mechanism formed of relatively movable elements operatively engaged together, said mechanism operatively engaging said base member and said second member and including pivotally supported relatively movable levers, one of said levers presenting a cam surface engaged by the other of said levers, and means for actuating one of said levers.

28. In a machine of the character set forth, the combination of a base member, a second member movable on said base member, and means for moving said second member on said base member comprising mechanism formed of relatively movable elements operatively engaged together, said mechanism including relatively movable levers pivoted to said base member and said second member, respectively, and engaging each other, and means for actuating said mechanism.

29. In a machine of the character set forth, the combination of a base member, a second member movable on said base member, and means for moving said second member on said base member comprising mechanism formed of relatively movable elements operatively engaged together, said mechanism operatively engaging said base member and said second member and including pivotally supported relatively movable levers engaging each other, and means for actuating said mechanism, the points of pivotal support of said levers being at opposite sides of the point at which said levers operatively engage each other.

30. In a machine for cutting threads on an object, the combination of a holder-member for the object to be threaded, a cutting-member for threading the object, said holder-member being movable toward and away from said cutting-member during the thread-cutting operation to produce backing-off of the threads, a support for said holder-member, and means for effecting said movement of said holder-member comprising mechanism formed of relatively movable elements operatively engaged together, said mechanism operatively engaging said support and said holder-member, and means for effecting relative movement of said elements.

31. In a machine for cutting threads on an object, the combination of a base member, a second member movable on said base member, and means for moving said second member on said base member comprising mechanism formed of relatively movable elements operatively engaged together, said mechanism operatively engaging said support and said holder-member, and means for effecting relative movement of said elements.

object, the combination of a support, a rotatable holder-member for the object to be threaded, a cutting-member for threading the object, said holder-member being movable on said support toward and away from said cutting-member during the thread cutting operation to produce backing-off of the threads, and means for effecting said last-

referred-to movement of said holder-member comprising mechanism formed of relatively movable elements operatively engaged together, said mechanism operatively engaging said support and the part on which said holder-member is rotatable, and means for effecting relative movement of said elements. 10 15

OTTAR S. LEE.
